PERCUSSIVE DRIFT DRILL

Orville Phipps, near Denver, Colo.

Application July 22, 1949, Serial No. 106,105

1. Claim. (Cl. 308—4)

This invention relates to the art and practice of percussive rock and ore drilling for the development of deep blast holes therein, and more particularly to such drilling performed in a non-vertical direction and hence productive of frictional drag between the drill stem and bit assembly and the walls of the drilled hole, and has an object to provide improved cooperating means and facilities constituting a percussive drill bit and stem assembly employable with conventional actuating means and adjuncts to enhance the economy and efficiency of such drilling operations.

A further object of the invention is to provide an improved construction and separable interrelation of drill bit, coupler, and stem sections constituting an assembly operable for the percussive drifting of deep blast holes in association with conventional actuating means and adjuncts.

A further object of the invention is to provide improved means for the intercoupling of bit and drill stem sections in an assembly operable for the percussive drifting of deep blast holes with celerity and efficiency.

A further object of the invention is to provide improved means for the intercoupling of bit and drill stem sections in a percussive drift drill assembly characterized by minimum side friction and adequate bore-scavenging capacity.

A further object of the invention is to provide an improved percussive drill assembly convenient of operative manipulation in the development of drift holes at various inclinations and to various desired depths, that is especially susceptible of length variation at will, that is rugged, durable, and efficient in use, and that is adapted to facile production in a wide range of desired sizes by known means and available agencies.

With the foregoing and other objects in view, my invention consists in the construction, arrangement, and operative combination of elements hereinafter set forth, pointed out in my claim, and illustrated by the accompanying drawings, in which—

Figure 1 is a somewhat diagrammatic elevation of a representative embodiment of the invention as assembled and associated with conventional actuating means ready for practical use. Figure 2 is a fragmentary elevation, on a relatively enlarged scale, of the bit end of the drill assembly according to Figure 1 in operative relation with a drift hole developed. Figure 3 is a fragmentary, detail elevation, on a further enlarged scale, of a separable joint characterizing the drill assembly shown in the pre-

ceding views. Figure 4 is a fragmentary, detail section, taken substantially on the indicated line 4—4 of Figure 3. Figure 5 is a transverse section taken on the indicated line 5—5 of Figure 4. Figure 6 is a fragmentary, detail elevation, partly in section and on the same scale as Figures 3, 4 and 5, of the bit end of the assembly shown in Figures 1 and 2.

In the percussive drifting of blast and analogous holes at various inclinations to the vertical in rock and ore bodies, it is conventional practice to use a mechanical hammer powered by hand, fluid pressure, or electricity, to percussively drive, advance, and simultaneously rotate a drill assembly comprised from a plurality of interconnected stem sections carrying a bit on the section free end remote from the hammer; said sections and bit being separably interrelated for simultaneous rotation and reciprocation and being characterized by a continuous axial bore opening through the bit for the transmission of fluid through the hammer and drill assembly to ejection from the bit for cooling of the bit working face and scavenging of the bore under development. As will be manifest, non-vertical drifting by means of conventional drill assemblies is productive of a drag of the assembly against the lower wall of the bore as the depth of the latter increases, thus lowering the percussive efficiency of the hammer evidenced at the face of the bore, impeding the effectiveness of bore scavenging, and rapidly wearing the frictionally-engaged surfaces of the assembly, and the instant invention is hence directed to the provision of a novel and improved percussive drill assembly construction incorporating all of the advantages of conventional analogous arrangements and free from the operative disadvantages just noted.

In the construction of the improvement as shown, the numeral 10 designates a conventional mechanical hammer operable by means of fluid pressure through a line 11 to percussively drive and simultaneously rotate a drill assembly end-engaged in its chuck 12 and supported through a guide 13 in a usual manner. The hammer 10 is carried by and for altitudinal and angular adjustment relative to the usual mounting post 14 and is served by the customary line 15 where-through fluid under pressure, preferably water, may be supplied through the hammer and its chuck 12 to the axial bore of the drill assembly, and a separate fluid pressure line 16 serves the mechanism of the hammer effective to axially advance the chuck 12 and drill assembly engaged

therein. All of the foregoing is conventional construction typical of usual percussive drift-drilling operations and in and of itself forms no part of the instant invention, being herein illustrated and described as but representative of known agencies and techniques susceptible of efficiency enhancement through association with the improvements hereinafter elaborated.

The improved drill assembly of the invention is adapted to operatively mount and percussively drive a bit of the type shown and described in my United States Patent No. 2,507,221, dated May 9, 1950, which bit is characterized by a generally frusto-conical body 17, tungsten-carbide alloy blocks 18 inset as the cutting elements of its working face, an axial, internally-threaded socket 19 opening through its lesser end for mounting engagement with a drill stem section, flutes 20 longitudinally interrupting its exterior wall and opening through its working face between the blocks 18 for scavenging clearance of cuttings, and flow channels 21 communicating between the socket 19 base and outlets in the flutes 20 and bit working face for ejection of cooling and scavenging fluid transmitted to the bit through the stem sections, and the said improved assembly is comprised, in addition to the bit, from an appropriate number of stem sections 22 and section couplers 23, hereinafter specifically described.

The stem sections 22 are alike, save as to length which may vary within the contemplation of the invention from a few inches to a maximum approximating five feet, except for the section unit engageable with the hammer chuck 12 which is modified at one end in any conventional manner suited to driving cooperation with said chuck, and each presents, in a rigid, integral unit, a straight shaft body of desired diameter, length, and exterior surface contour, a threaded stud 24 coaxial with and projecting from each end of said body, an annular bearing shoulder 25 perpendicular to the body axis marking the junction of each body end with the associated stud 24, and an axial bore or channel 26 traversing and opening through the body and associated studs. The end of the initial section 22 remote from section engagement with the chuck 12 is furnished with a stud 24 and shoulder 25 identical with the corresponding elements of the other stem sections and is provided with the bore or channel 26, and the sections 22 employable in a given operation will include a variety of section lengths appropriate for the constitution of variable length drill assemblies adequate for initiation and development of the desired drift hole. The ends of the stem sections 22 providing the shoulders 25 may be expanded relative to the body portion therebetween, as shown, or may be of the same diameter as said body portion, as may be determined by factors of requisite strength and pertinent economy.

Interrelation of the sections 22 in a coaxial assembly of desired length is accomplished through the agency of the couplers 23, one of which is employed to complete each joint of the assembly intermediate the bit mounting and driving engagement with the hammer chuck 12. Each coupler 23 is a rigid, integral unit developed on, in, and about a generally cylindrical body of a diameter equalling that of the stem shoulders 25 and a length more than twice the length of a stem stud 24. Ends of the coupler 23 body are finished perpendicular to the body axis for abutting engagement against shoulders 25 of the stem sections 22, and each of said coupler body

ends is intersected by a coaxial, internally-threaded socket 27 of a depth somewhat exceeding the stud 24 length and adapted to cooperatively accommodate such stud; inner ends of said sockets 27 in a given coupler being spaced apart by a partition integral with the coupler body through which an axial throat 28 opens to continue the bore or channel 26 of the sections 22 interconnected by the coupler. Exteriorly, each coupler 23 body is formed with a plurality, at least three, of like, angularly-spaced, longitudinal channels defined by and opening radially between like, integral ribs 29 outstanding from and longitudinally of the body in paired relation and in such convexity of their exterior margins as results in a merging of the rib ends with the body contour at the ends of the coupler and a maximum channel depth at the coupler mid-portion; the rise of said ribs away from the coupler body being definitive of a maximum coupler diameter at the unit mid-section approximately one-eighth of an inch less than the working face diameter of the bit to be employed with the assembly. In the midlength of each channel defined between the paired ribs 29, a block 30 of hard, abrasion-resistant material, such as tungsten-carbide alloy, is closely fitted to bear against the channel floor and rib faces and permanently secured, as by means of welding or brazing, in an outer surface contour conforming to the rib 29 convexity and the coupler transverse circular outline determined by said ribs. The blocks 30 preferably do not extend the full length of their mounting channels and are end-beveled, as shown, well short of the corresponding channel ends. The ribs 29 defining adjacent sides of the angularly-spaced channels outstand in an angular divergence productive of a flute or channel 31 longitudinally of the coupler wherethrough material and fluid incident to scavenging of the drift hole may pass during operation of the assembly.

The external threads of the studs 24 and the mating internal threads of the bit socket 19 and coupler sockets 27 may, of course, be of any type and design suited to accomplish the interengagements for which they are provided, but operative advantages result when said threads are of the non-binding, sinuously-profiled type in the specified diameter and length proportions set forth in my pending application for United States patent, Serial No. 681, filed January 6, 1948, and now abandoned. Whatever type and design of thread may be employed for the studs 24 and their receiving sockets, it is immediately apparent that all such threads should be similarly pitched in a direction so correlated with that of chuck 12 rotation as to maintain the threaded joints in tight interengagement during operation of the drill assembly, and that the depths of the stud-receiving sockets should exceed the stud lengths to assure percussion-transmitting, bearing engagement of the stem shoulders 25 and the associated coupler 23 or bit 17 ends.

In the operation of the improved drill assembly constructed and organized as shown and described, it is readily to be seen that the couplers 23 serve to unite the stem sections 22 and bit 17 in a solid, coaxial assembly highly effective in the transmission of forces applied through the hammer 10 and adapted to the pressure supply of cooling and scavenging fluid to the bit working face. The use of the couplers 23 in a diameter slightly less than that of the bit working face permits the rotational and reciprocating frictions incident to assembly actuation to be

concentrated on the limited areas of the wear blocks 30 as the latter ride on the drift hole walls, thereby materially reducing the operational friction loss, minimizing wear damage to the equipment, preserving alignment of the elements for efficient force transmission, and maintaining clearance between the hole lower wall and the stem sections 22 wherethrough effective scavenging may be had with the aid of the bit flutes 20 and coupler flutes 31.

Since changes, variations, and modifications in the form, construction, and arrangement of the elements shown and described may be had without departing from the spirit of my invention, I wish to be understood as being limited solely by the scope of the appended claim, rather than by any details of the illustrative showing and foregoing description.

I claim as my invention:

In a coupler for percussive drill string sections 20 having an axially-elongated, generally-cylindrical body connectible with and as a coaxial link between adjacent section ends, a flow channel axially of said body, and a plurality of like, convex rib units outstanding from and longitudinally of said body in a uniform angular spacing definitive of straight, unobstructed flutes therebetween, means for minimizing frictional drag and coupler wear effects incident to percussive drill string actuation within a well bore, said means 30 comprising, a straight channel centrally and exteriorly intersecting the full length of each of

said rib units to condition the unit exposed surface for minimum frictional coaction with well bore walls as a pair of narrow, spacedly-parallel, convexly-margined rib elements end-merging with the body ends, a separate, preformed, alloy wear block of less length than the rib elements fitted to seat within and to fill the central portion of each unit-intersecting channel between the rib elements thereof in conforming engagement of its side and bottom surfaces with the channel and rib element surfaces contacted thereby, a permanent bond uniting the full contacting areas of said block and its mounting, and an exposed wear surface on said block conformed to the exposed margins of its associated rib elements.
